INSTRUMENT FOR CLOSING THE URETHRA

Hans Salm, Munich, Germany

Application August 31, 1950, Serial No. 182,520
In Germany April 27, 1949

9 Claims. (Cl. 128—1)

1

The object this invention aims at is to provide an instrument which enables to seal the urethra hermetically in a dependable manner. Such an instrument is requested for inst., if the sphincter fails to function, with chronic nocturnal enuresis etc. The contrivance according to this invention may be used also as a condom.

The instrument according to this invention is characterized by a hollow body, open at one extremity thereof, made of an elastic material, to be inserted into the mouth of the urethra. This body is provided with a contraction between an outer flange and an inner enlargement, so that due to the elasticity which prevails between the flange and the enlargement a biasing pressure is exercised on the parts of the urethra which are located near the contraction of the hollow body, whereby the complete seal of the urethra is assured.

A special implement is used for inserting the said device into the urethra. This former consists of a mandrel with a head thereon, which, when an axial thrust is applied to the mandrel, will have a biasing effect on the cap of the enlargement; the said implement has, moreover, a tapered part for mutual engagement with expanding members of a retaining and guiding sleeve for the mandrel, which members have been shaped as jaws to grip a stiffening of the flange.

The figures in the attached drawing are showing diagrammatically an embodiment of this invention, of which

Fig. 1 is a vertical section through the instrument as per this invention together with the implement for inserting the contrivance into the urethra,

Fig. 2 is a section along line A—B of Figure 1,
Fig. 3 a section along line C—D of Figure 1,
Fig. 4 a vertical section of the case for the instrument.

The device consists of a hollow body of elastic material, such as rubber, to be inserted into the mouth of the urethra. This hollow body is provided with a contraction 3 between an outer flange 1 and an inner enlargement 2. The enlargement 2 is closed at its face by a cap 4, which has been drawn inwards to assume the shape of a dish, what is very important with regard to the stability of the shape and the dependability of the seal. The body (1, 2, 3, 4) is provided with an insertion 5 in the shape of a network of mutually crossing filaments. The special purpose of this network of crossing filaments is to provide that, if the enlargement 2 is stretched in

the direction of the arrow 6, this enlargement assumes an exactly cylindrical shape, which corresponds in diameter to that of the contraction 3. The network of filaments is intended, moreover, to balance all stresses which might arise in the rubber body and thus to make for the necessary tearing strength. The cap 4 is provided with an additional insertion 7, e. g. in the shape of a disk of corduroy, whose diameter must be smaller than the inner diameter of the contraction 3. This insertion serves as an abutment for the inserting implement—to be described below—if the body (1, 2, 3, 4) is stretched in the direction of the arrow 6. This insertion protects, moreover, within the sphere of the cap 4 the network 5 against mechanical destructions caused by introducing the mandrel.

Within the flange 1 is located a stiffening 8, preferably in the shape of a metal disk, which is indented at its periphery. The network of filaments is anchored to this stiffening 8 (i. e. at the teeth of the metal disk). Besides this the flange 1 is reinforced by filament insertions 9 arranged in zig-zag, which surround the stiffening 8.

The introduction of the rubber body into the urethra is performed by means of a mandrel 10, which at one of its extremities is provided with a ball-shaped head 11. The concavity of the cap 4 is curved along the convexity of the ball-shaped head to avoid lateral slipping of the head off the cap. The mandrel 10 is able to perform a gliding movement in a, e. g. metallic sleeve 12, which latter acts as a guide. In its fore part the sleeve is provided with peripheral slots 13, which form expanding members 14, which in their turn form both jaws 15 and abutment faces 16. The intermediate space 17 between the jaws 15 and the abutments 16 is contracted and serves for co-operation with a tapered part 18 of the mandrel 10, so that when the mandrel 10 is shifted in its sleeve 12 in the direction of the arrow 19 the members 14 become expanded. At the free extremity of the mandrel is a pressure disk 20 for the action of the thumb of the hand which is handling the device. The free extremity of the sleeve 12 is correspondingly shaped as an abutment for the index and middle finger of the same hand.

The manipulation of this device is as follows: The mandrel 10 together with its sleeve 14 and the parts of the latter is at first applied to the body (1, 2, 3, 4) in the position which may be seen in Fig. 1. The pressure disk 20 and the abutment 21 are brought in operating position between the thumb of the hand in action and the index and

middle finger of the same hand, and then a pressure is exerted by the thumb on the disk 20 in the direction of the arrow 19. By moving the mandrel 10 within the sleeve 12 the tapered part 18 is brought to mutual engagement with the contractions 17 of the expanding members 14, so that the latter are expanded to the effect that the stiffening 8 of the flange 1 is clamped between the jaws 15 and the abutments 16 of the expanding members and thus the rubber body becomes retained during the continued advance of the mandrel 10. The head 11 of the mandrel 10 strikes during the continued axial displacement of the latter the inner wall of the cap 4. The enlargement 2 is stretched and shrunk against the effect of its elasticity to assume the cylindrical shape with the diameter of the contraction 3, the filament network 5 assuring the stability of the shape of this cylinder. Now the rubber body has been shaped to the diameter which allows its introduction into the urethra. If this has been accomplished the mandrel 10 becomes released of the pressure of the thumb and is returned subsequently, owing to the elasticity of the rubber body. The rubber body assumes once more the shape shown in Fig. 1, wherein the parts of the urethra which are near the contraction 3 are engaged by the 1, 2 and 3 to form a seal by clamping them together. Now the mandrel is removed together with its sleeve.

According to this embodiment of this invention the pressure disk 20 has been shaped at the same time as a cover for a case 22, in which the entire instrument, i. e. the rubber body as well as the stretching implement are kept, if they are out of use. In this example the cover 20 has been provided with a threaded part for having it screwed on to the case.

What I claim is:

1. A device for closing the urethra comprising a substantially cup-shaped body of elastic material suitable to be inserted into the mouth of the urethra with its closed end first; a flange at the open end of said body, an inner enlargement at the closed end of said body, said flange and enlargement defining between themselves an annular contraction of said body serving as a seat for parts of the urethra clamped between said flange and expansion, and means provided inside said body to increase the clamping pressure between said flange and said expansion.

2. A device for closing the urethra comprising a substantially cup-shaped body of elastic material suitable to be inserted into the mouth of the urethra with its closed end first; a flange at the open end of said body; an inner enlargement at the closed end of said body, said flange and enlargement defining between themselves an annular contraction of said body serving as a seat for parts of the urethra clamped between said flange and expansion, and reinforcing means embedded in said body suitable to ensure a cylindrical form of said body on applying to the closed end thereof axial pressure from the inside.

3. A device for closing the urethra comprising a substantially cup-shaped body of elastic material suitable to be inserted into the mouth of the urethra with its closed end first; a flange at the open end of said body; an inner enlargement at the closed end of said body, said flange and enlargement defining between themselves an annular contraction of said body serving as a seat for parts of the urethra clamped between said flange and expansion, and a network of filaments em-

bedded in said body suitable to ensure a cylindrical form of said body on applying to the closed end thereof axial pressure from the inside.

4. A device for closing the urethra comprising a substantially cup-shaped body of elastic material suitable to be inserted into the mouth of the urethra with its closed end first, a flange at the open end of said body, a stiffening in said flange, an inner enlargement at the closed end of said body, said flange and enlargement defining between themselves an annular contraction of said body serving as a seat for parts of the urethra clamped between said flange and expansion, and a network of filaments embedded in said body and anchored to said stiffening, said network ensuring a cylindrical form of said body on applying to the closed end thereof axial pressure from the inside and increasing the clamping pressure in parts of the urethra clamped between said flange and expansion on releasing the axial pressure on the closed end of said body.

5. A device as defined in claim 4 comprising in addition reinforcing filaments arranged in zig-zag around the stiffening in the flange.

6. A device for closing the urethra comprising a substantially cup-shaped body of elastic material suitable to be inserted into the mouth of the urethra with its closed end first; an inwardly concave cap-like seat at the closed end of said body; a flange at the open end of said body, and an inner enlargement at the closed end of said body, said flange and enlargement defining between themselves an annular contraction of said body serving as a seat for parts of the urethra clamped between said flange and expansion.

7. A device for closing the urethra comprising a substantially cup-shaped body of elastic material and a detachable handle to facilitate inserting of said body into the mouth of the urethra with its closed end first; an inwardly concave cap-like seat at the inner closed end of said body, a flange at the open end of said body, an inner enlargement at the closed end of said body, said flange and said enlargement defining therebetween an annular contraction of said body serving as seat for parts of the urethra; a tapered end at said handle ending into an enlarged head engaging the cap-like seat of the closed end of the elastic body; and a sleeve slidably mounted on said handle and forming two spaced elastic annular extensions, said extensions engaging in operative position the annular contraction and the flange of said elastic body respectively.

8. A device for closing the urethra comprising a substantially cup-shaped body of elastic material and a detachable handle to facilitate inserting of said body into the mouth of the urethra with its closed end first; an inwardly concave cap-like seat at the inner closed end of said body, a flange at the open end of said body, an inner enlargement at the closed end of said body, said flange and said enlargement defining therebetween an annular contraction of said body serving as seat for parts of the urethra; a tapered end at said handle ending into an enlarged head engaging the cap-like seat of the closed end of the elastic body; a sleeve slidably mounted on said handle and forming two spaced elastic annular extensions, said extensions engaging in operative position the annular contraction and the flange of said elastic body respectively, and reinforcing means embedded in said body, which reinforcing means ensure on the one hand a cylindrical form of said body when it is extended and pushed by said handle into the urethra, and on

5

the other hand increase the clamping pressure on the parts of the urethra gripped between said flange and inner enlargement, when said body is left in the urethra after removal of the handle.

9. A device as defined in claim 8 comprising spaced parallel axially extending slots in said elastic sleeve.
